UNITED STATES PATENT OFFICE.

CHARLES L. WILSEN, OF MANETTE, WASHINGTON.

BUCKET ELEVATOR.

1,375,881.

Specification of Letters Patent. Patented Apr. 26, 1921.

Application filed March 17, 1920. Serial No. 366,630.

To all whom it may concern:

Be it known that I, CHARLES L. WILSEN, a citizen of the United States, residing at Manette, in the county of Kitsap and State 5 of Washington, have invented a certain new and useful, Improvement in Bucket Elevators, of which the following is a specification.

My invention relates to improvements in 10 bucket elevators and the object of my invention is to provide a bucket elevator that is adapted for handling heavy materials such as coal, ore, stone, sand, gravel, grain, phosphate rock and the like or for use in 15 fertilizer and lime plants.

Another object of my invention is to provide a bucket elevator that is adapted for use on, and permanent installation in, colliers to expedite the discharging of their cargoes 20 at docks or for coaling ships at sea, and that is further adapted for use on, and permanent installation in, coal scows or barges to expedite the coaling of ships in harbors where no regular coaling facilities are avail- 25 able.

A further object of my invention is to provide a bucket elevator adapted to be inclosed in a casing or trunk having selective discharge ports with associated tripping 30 mechanisms arranged successively therein for the purpose of discharging the contents of the buckets at any desired height, as, for example, discharging a cargo from a low lying ship or barge to a low or high dock at 35 low or high tide or through a side port of a large vessel or warship directly to the bunkers of the same.

A still further object of my invention is to provide an inclosed bucket elevator that 40 is adapted to be operated by a direct connected motor or by chain drive from a winch or other available power.

A still further object of my invention is to provide an inclosed bucket elevator that 45 may be constructed from standard commercial plates, angles, channels, pipes, rods and the like, which will combine simplicity, durability, strength and economy in its construction and which will readily permit of 50 repairs being made at any time without special equipment or facilities.

A still further object of my invention is to provide a bucket of the side and bottom dump type adapted for operation in my in-

closed elevator trunk, the bucket to be actuated when desired by means carried by the casing of the said elevator.

A still further object of my invention is to provide a bucket with a tipping bottom and a swinging door on one of its sides, the bucket being adapted for operation in my inclosed elevator and having novel door operating devices adapted to be actuated by tripping and locking mechanisms carried by the casing of the said elevator to positively insure synchronous movement of the said bottom and door during the tripping and opening of the same to discharge the load carried by the said bucket.

With the above and other objects in view 70 which will appear as the description proceeds, my invention resides in the novel construction, combination, adaptation and arrangement of parts hereinafter described and claimed.

I accomplish these objects by devices illustrated in the accompanying drawings wherein:

Figure 1 is a view partly in side elevation and partly in vertical cross-section of an 80 elevator constructed in accordance with my invention, a fragment of a barge in which the elevator is installed being shown in cross-section and a fragment of a dock upon which the elevator is arranged to deliver 85 being shown in elevation. Fig. 2 is a fragmentary view in vertical section of the upper end of the elevator trunk; Fig. 3 is a view in cross-section substantially on a broken line 3, 3 of Fig. 2, the chain and 90 buckets being omitted. Fig. 4 is a view partly in vertical section and partly in elevation of the upper end of the trunk shown in Fig. 2. Fig. 5 is a fragmentary sectional view of a detail of the invention. Fig. 6 is 95 an enlarged fragmentary view showing the elevator trunk in cross-section and one of the elevator buckets in plan. Fig. 7 is a view in vertical cross-section substantially on a broken line 7, 7 of Fig. 6, showing an 100 elevator bucket in a dumping or discharging position.

Referring to the drawings throughout which like reference numerals designate like parts, the numeral 10 designates an upright 105 elevator trunk of an ordinary standard type of construction that is provided with a continuous passageway 11 through which buckets

or flights may travel and that is provided at or near its respective ends with transverse shafts 12 and 13 whereon are mounted driving wheels 14 of a form of construction 5 more clearly shown in Figs. 2 and 3.

The driving wheels 14 preferably each comprise cast hubs 15, solid metallic webs 16, and cast teeth or chain engaging members 17. Two of the wheels 14 are preferably 10 provided on each of the transverse shafts 12 and 13.

Disposed upon the wheels 14 are two endless conveyer chains 18 and 20 to which are secured buckets 21, the buckets 21 each being 15 provided on the rear side with two lugs 22 that are pivotally secured to the chains 18 and 20, the length of each link in the chains 18 and 20 preferably being equal to the distance between the pivot points of the two 20 lugs 22.

The lowermost shaft 13 is preferably mounted in vertically adjustable bearings as indicated in Fig. 1 so that any slack in the conveyer chains may be taken up and 25 the upper shaft 12 is preferably provided on the exterior of the elevator trunk with a sprocket wheel 19 which may be connected by the usual form of sprocket chain, not shown, with any suitable driving mechanism.

30 Each of the buckets 21 is provided on its rear side with four guide rollers 25 disposed, two on each side of each bucket in spaced relation as shown in Fig. 7 and projecting sidewise from the plane of the side of the bucket so that they may be caused to travel in continuous channel shape trackways 26 35 that are secured to the sides of the elevator trunk.

The channel shaped trackways 26 not only 40 serve as guides for the rollers and supports for the conveyer buckets 21 but they also serve to brace and reinforce the sides of the conveyer trunk.

The buckets 21 are of substantially rectangular cross-sectional shape and are provided with tilting bottoms 27 having side flanges 28 that are secured by pivots 30 to the sides of the buckets so that the bottoms 27 may assume the inclined position shown 50 in Fig. 7. The rear sides of the buckets are each provided with an internally projecting lip 31 that is arranged to engage the rear end of the bottom 27 and serves as a stop to limit the swinging movement of such bottom. The rear side of the bucket adjacent the bottom edge thereof is curved as at 32 55 on a radius whose center is the pivot 30 so that a close connection will be made between the rear edge of the bottom 27 and the 60 curved portion 32.

The front edge of the bottom 27 is preferably reinforced with a relatively heavy transverse strip 33 which also serves as a weight to insure the tilting of such bottom 65 when it is released.

The front side to the bucket is provided at the top edge with a rigid cross bar 34 to which prongs or digging members 35 are fixedly secured.

Disposed below the cross-bar 34 is a swing- 70 ing front door 36 that is hinged on a pivot 37 and that is connected by links 38 with the upper portion of the flanges 28 above the pivots 30 so that when the bottom member 27 is swung into the angular position 75 shown in Fig. 7 the front door 36 will be swung outwardly to permit the free discharge of material from the bucket.

Secured to the bottom 27 of the bucket is a rearwardly projecting arm 40 having a 80 roller 41 journaled in its outer end, which roller 41 is adapted to roll upon a continuous trackway 42 as the buckets move within the conveyer trunk, the arm 40 serving to hold the bottom 27 and front door 36 in a 85 closed position when the roller 41 is in normal engagement with the trackway 42.

For the purpose of permitting the bucket bottom 27 and front door 36 to assume the 90 open position shown in Fig. 7, I have provided at suitable intervals in the trackway 42 a plurality of swinging gates or trip doors 43 that are each secured at their bottom ends to pivot shafts 44 and that are 95 adapted to be tilted rearwardly into the position shown in Fig. 7 to permit the rollers 41 to enter the openings left by such doors and thereby allow the bottoms 27 and front doors 36 of the buckets to be swung into 100 their open positions.

Disposed above the doors 43 and projecting from the trackways 42 are guard members 45 that are arranged to engage with the rollers 41 and close the bottoms and front doors of the bucket after they have passed 105 the discharging position.

The front side of the elevator trunk 10 is provided at a plurality of intervals, one above another, with discharge openings 46, 110 that are arranged to be closed by swinging doors 47, which are secured to transverse shafts 48.

Disposed at the bottom of each of the openings 46 is a discharge chute 50 that is arranged to deliver material into a transversely disposed chute 51 by which such material may be discharged onto a dock 52 or 115 may be conducted to any other desired location as to the bunkers or coal bins of a ship.

The chute 51 is preferably supported by 120 a cable 53 that passes upwardly over a pulley 54 that is mounted for rotation on a bracket 55 on the upper end of the elevator trunk 10, the cable thence passing downwardly and being wound about a drum 56 125 so that the height of the chute 51 may be adjusted.

The locations of the discharge openings 46 bear a definite relation to the locations 130 of the trip doors 43 in the trackways 42 and

the discharge doors 47, by which the openings 46 are closed, and are preferably connected with the trip doors 43 in such a manner that the two will be operated simultaneously.

For the purpose of opening and closing the uppermost door 47 the shaft 48 is provided with a worm wheel 57 that meshes with a worm 58 on a vertical shaft 60 that 10 is journaled in bearing brackets 61 and extends downwardly to a point within convenient reach of the elevator operator where it is provided with a hand wheel 62 by which it may be turned.

15 For the purpose of opening and closing the uppermost trip door 43 simultaneously with the opening and closing of the uppermost discharge door 47 the shaft 44 is provided with a worm wheel 63 that meshes 20 with a worm 64 on a short transverse shaft 65 that is connected by bevel gears 66 with the vertical shaft 60 so that when such vertical shaft is rotated to open or close the discharge door 47 the trip door 43 will be 25 opened or closed simultaneously therewith.

The discharge doors 47 and corresponding trip doors 43 below the top ones just above described are opened and closed by similar mechanism, the second doors from the top 30 being controlled by mechanism connected with a sleeve-shaft 67 that is disposed on the shaft 60, see Fig. 5, and has a handwheel 68 on its bottom end and the lowermost doors being controlled by mechanism that is 35 connected with another sleeve-shaft 70 that fits over the sleeve-shaft 67 and is provided at its bottom end with a hand wheel 71 all as more clearly shown in Fig. 1.

It will be understood that as many discharge openings as desired may be provided 40 and that they may all be opened and closed by mechanism similar to that above described.

The bottom end of the elevator trunk is 45 preferably of substantially the shape shown in Fig. 1 and has a normally open front side 72 that is arranged to be closed by a vertically movable guard member or hood 73 having an outwardly projecting angular lip 74 50 on its bottom end. The guard member 73 is adjusted vertically by turning a handwheel 75 on a shaft 76 whereon is secured a pinion 77 that meshes with a rack 78 on the guard member.

55 The guard member 73 serves to regulate the feed of the material to the elevator buckets and determines the angle of repose of the surface of the material that the buckets scoop into.

60 The bottom end of the trackway 42 on which the rollers 41 travel is enlarged or bulged as at 49 Fig. 1 so that as the buckets pass around the wheels 14 at the lower end of the trunk the rollers 41 will be supported 65 by the bulged portion 49 and will hold the

bottoms 27 and front doors 36 of the buckets in a closed position as the buckets begin to fill with material.

Constructing the buckets with the hinged bottom and front side so that a side discharge of the material may be had makes it possible to discharge the material at any point between the bottom and top of the elevator instead of being able to discharge at the top of the elevator only as is customary 70 with bucket elevators and thereby not only releases the material at the desired elevation but also saves a great deal of power that would otherwise be expended if the material were all elevated to the top of the elevator 75 trunk and then permitted to run down a chute to the desired point of delivery.

My apparatus is particularly well adapted 80 for coaling freight ships which are usually coaled through scuttles on the weather deck 85 thereby liberating a great amount of coal dust and dirt which permeates the ship and must necessarily be cleaned up. With my device and dust tight chutes the coal could be delivered through the side ports and directly into the bunkers of the vessel with practically no dust and dirt.

This elevator is constructed chiefly of standard size plate, channels, angles, round bars and pipe thus making a cheap, simple 90 and strong construction and making the device easy to repair.

The elevator is adapted for handling almost any kind of coarse heavy material and is particularly useful for elevating coal, ore 100 and gravel.

From the foregoing description taken in connection with the accompanying drawings, the advantages of the construction and of the method of operation will be readily 105 apparent to those skilled in the art to which the invention relates, and while I have described the principle of operation of the invention, together with the device which I now consider to be the best embodiment 110 thereof, I desire to have it understood that the device shown is merely illustrative and that such changes may be made when desired as are within the scope of the invention.

What I claim is:

1. In an elevator of the class described an upright trunk, having a plurality of discharge openings arranged at different elevations, endless conveyer chains movable within said trunk, buckets carried by said chains, each of said buckets having a hinged bottom whose front edge is arranged to swing downwardly and a hinged front side whose bottom edge is arranged to swing outwardly, means carried by said buckets 120 for opening and closing said bottom and said swinging front side and devices within said elevator trunk for controlling said opening and closing means.

2. In an elevator of the class described, an 130

upright trunk having a plurality of discharge openings arranged one above another, endless conveyer chains movable within said trunk, elevator buckets secured to said chains, guide rollers journaled on the sides of said buckets, trackways rigid with said trunk for the reception of said guide rollers, a tilting bottom for each of said buckets, a hinged front side for each of said buckets, 10 means for insuring synchronous opening and closing of the tilting bottom and hinged front side of each bucket, an arm secured to each of said tilting bottoms for opening and closing the same, a trackway rigid with said 15 trunk for the reception of said arms, and means provided in said trackway for releasing said arms to permit the opening of the bottoms and sides of said buckets.

3. An elevator of the class described comprising an upright elevator trunk having a plurality of discharge openings arranged one above another, endless conveyer chains movable in said elevator trunk, conveyer buckets secured to said conveyer chains, a 20 tilting bottom provided in each of said buckets, a swinging front side hinged at its top edge to each of said buckets, links connecting said swinging front side with said bottom to insure simultaneous opening and 25 closing movement of said front side and said bottom of each bucket, arms secured to each of said bucket bottoms and projecting rearwardly therefrom, rollers journaled in the ends of said arms, a continuous trackway 30 for said rollers whereby said arms are normally caused to hold said buckets in a closed position and trip doors interposed within said trackway in predetermined relation to said discharge openings in said trunk and arranged to be opened to release said arms and selectively permit the opening of said buckets opposite any desired discharge 35 opening.

4. An elevator of the class described comprising an upright trunk having a plurality of discharge openings arranged one above another, wheels mounted for rotation at opposite ends of said trunk, endless conveyer chains arranged to run on said wheels, conveyer buckets secured to said conveyer chains, a tilting bottom provided in each of said buckets each of said bottoms having upturned side flanges that are pivotally connected to the sides of the bucket, a swinging 40 front side hinged at its top edge to each of said buckets, links connecting said swinging front side with the side flanges of said bottom to insure simultaneous opening and closing movement of said front side and said 45 bottom, arms secured to said bucket bottoms and projecting rearwardly therefrom, rollers journaled in the ends of said arms, a continuous trackway for said rollers whereby said arms are normally caused to hold 50 said bucket bottoms in a closed position, said trackway having a bulge at its bottom end to hold said bottoms closed as said buckets are passing said lowermost wheels, trip doors interposed within said trackway in predetermined relation to said discharge 55 openings in said trunk and arranged to be tilted rearwardly to release said arms and allow the opening of the bottoms and sides of said buckets, doors for closing the discharge openings in said trunk and means for simultaneously moving said last named doors and said trip doors into open or closed position.

In witness whereof, I hereunto subscribe my name this 28th day of February, A. D. 1920.

CHARLES L. WILSEN.
